[57] ABSTRACT

Plasma lipid levels in a mammal are reduced by compounds such as 4,4'-methylenebis(2,6-di-tert-butylphenol).

A preferred embodiment encompasses methods and compositions for reducing plasma lipid levels based on compounds having the formula

wherein

R^a and R^b are tertiary alkyl radicals, most preferably tert-butyl,

R and R^c are alkyl radicals of one to four carbons, and

R^d and R^e are independently selected from hydrogen or methyl.

METHOD AND COMPOSITION FOR REDUCING PLASMA LIPID LEVELS

BACKGROUND OF INVENTION

This application is a continuation-in-part of application Ser. No. 705,295, filed Feb. 14, 1968, which in turn is a continuation-in-part of application Ser. No. 317,796, filed Oct. 21, 1963, both now abandoned.

In said earlier application Ser. No. 317,796, I disclosed methods and compositions (for reducing serum lipid levels) based on compounds having the formula

wherein

R_1 and R_2 are each selected from the group consisting of hydrogen and hydrocarbon radicals,

R is a hydrocarbon radical and

n and *p* are integers of from 0-4, such that when *n* and *p* are each at least 1, the radicals collectively represented by R may, on each phenyl moiety, be the same or different.

The hydrocarbon radicals are preferably alkyl of from 1-12 carbon atoms, cycloalkyl of from 6 to 12 carbon atoms, aryl of from 6-12 carbon atoms and aralkyl of from 7-12 carbon atoms.

SUMMARY OF THE INVENTION

This application, like said earlier application Ser. No. 705,295, is directed to an embodiment of the invention described within the aforementioned parent application; to wit, methods and compositions for reducing plasma lipid levels which are based on lipid lowering compounds having the formula

wherein

R^1 and R^2 are lower alkyl radicals (that is, alkyl radicals of 1 to 8 carbon atoms),

Y and Y¹ are hydrogen or lower alkyl radicals, and R³ and R⁴ is no more than about 5.

DESCRIPTION OF PREFERRED EMBODIMENTS

A preferred embodiment encompasses methods and compositions for reducing plasma lipid levels based on compounds having the formula

wherein

R^a and R^b are tertiary alkyl radicals, most preferably tert-butyl,

15 R and R^c are alkyl radicals of one to four carbons, and

R^d and R^e are independently selected from hydrogen or methyl.

A preferred compound is 4,4'-methylenebis(2,6-di-
20 tert-butylphenol). That compound is also known as di-C3,5-di-tert-butyl-4-hydroxyphenyl)methane. Other compounds are considered full equivalents. These are illustrated by the following non-limiting list:

25 4,4'-methylenebis(2,6-dimethylphenol)
4,4'-isopropylidenebis(2,6-di-tert-butylphenol)
4,4'-ethylidenebis(2,6-di-tert-butylphenol)
4,4'-methylenebis(2,6-di-sec-butylphenol)
4,4'-methylenebis(2-ethyl-6-tert-butylphenol)
30 4,4'-methylenebis(2-isopropyl-6-tert-butylphenol)
4,4'-methylenebis(2,6-di-tert-octylphenol)
4,4'-(3,3-hexylidene)-bis(2,6-di-tert-butylphenol)
4,4'-(2,2-butylidene)-bis(2,6-di-tert-butylphenol)
4,4'-(2,2-hexylidene)-bis(2-methyl-6-tert-
35 butylphenol)
4,4'-(1,1-hexylidene)-bis(2-ethyl-6-tert-butylphenol)
4,4'-(1,1-butylidene)-bis(2-isopropyl-6-tert-
butylphenol)

40 A skilled practitioner can readily see that compounds closely related to those named above are within the scope of this invention. Such compounds include phenols substituted with other alkyl groups, haloalkyl, such as trifluoromethyl, cycloalkyl, halogen, and the like. In 45 addition, closely related compounds within the scope of this invention include those with benzyl radical substitution. Such compounds are illustrated by:

50 4,4'-methylenebis-[2,6-bis(α -methylbenzyl)phenol]
 4,4'-methylenebis-[2-methyl-6-(α -methylbenzyl)phenol]
 4,4'-isopropylidenebis-[2-tert-butyl-6-(α -methylbenzyl)-phenol]

55 and the like.

In addition, positional isomers of the above compounds are within the scope of this invention. Such compounds are illustrated by 2,2'-methylenebis-(6-tert-butyl-p-cresol) and 2,2'-methylenebis-(6-tert-butyl-4-chlorophenol).

Furthermore, compounds not so heavily substituted are within the scope of this invention. Such compounds are illustrated by 2-tert-butyl-4,4'-methylenediphenol. In addition, the solubility of the active phenols can be altered by modifying the phenolic moiety. This is illustrated by esters and ethers of the phenols such as bis(3,5-di-tert-butyl-4-ethoxyphenyl)-methane.

The compounds of this invention can be prepared by methods well known in the art. Those di-(hydroxyphenyl)methanes in which the phenyl moieties are the same can be prepared by condensation of an appropriate phenol with an appropriate aldehyde, in the presence of base, as described in U.S. Pat. No. 2,807,653. Where the methylene bridge is substituted, a ketone can be used. U.S. Pat. No. 2,829,175 describes a method whereby anhydrous HCl or zinc chloride can be used to condense 2-, 2,4-, and 3-hydrocarbyl substituted phenols with an appropriate ketone. These methods can also be used to prepare those di-(hydroxyphenyl)methanes in which the phenyl moieties are different. In these cases two different phenols are condensed with an appropriate aldehyde or ketone, using an appropriate condensation procedure, and ordinary separation procedures, such as fractional distillation, crystallization and solvent extraction procedures, etc. can be used.

The compound, bis(3,5-di-tert-butyl-4-ethoxyphenyl)-methane which was mentioned above was made by the following procedure:

Dry sodium hydride was prepared from commercial sodium hydride in mineral oil. The mineral oil was removed by filtration under nitrogen and the solid was washed several times with dry petroleum ether (b.p. 30°-60°). After drying under a stream of nitrogen, the sodium hydride was a light gray solid. To 250 ml of pure dimethylsulfoxide which had been flushed with nitrogen, 4.8 g (0.2 mole) of the dry sodium hydride was added. This slurry was heated slowly to 65° and held at this temperature for one hour. Hydrogen was liberated as the dimethylsulfoxide anion was being formed and an almost clear solution resulted. After cooling to 30°, 21.2 g (0.05 mole) of (4,4'-methylenebis-2,6-di-tert-butylphenol) was added with stirring. This reaction was exothermic and the temperature of the mixture was held below 60° during the addition by using an ice bath for cooling and by using a slow rate of addition. When the solid phenol contacted the surface it turned a deep blue, however, on reacting

magnesium sulfate, and the volatiles removed on a rotary evaporator. The heavy oil which remained was found to crystallize when treated with isopropanol. Two recrystallizations of these crystals from isopropanol gave 5.34 g (22.3 per cent) of white crystals which melted at 111°-113°C. The VPC of this material showed only a minor impurity. The infrared spectrum did not have an OH stretching between 33-3800 cm⁻¹ and was consistent with the proposed structure of the diethyl ether of the starting phenol. Anal: Calcd. for C₃₃H₅₂O₂; C, 82.44; H, 10.90, molec. wt. 480.75. Found: C 82.5; H, 11.0, molec. wt. 489.

The compounds of this invention are remarkably effective in bringing about a rapid drop in circulating serum lipid levels using very low dosage regimens. This allows use in pharmaceutical forms both convenient for administration as well as pleasant for patient consumption.

To demonstrate the outstanding effectiveness of the compounds of this invention tests were performed on 26 dogs (Beagles) which are separated into four groups. The Control Group of 3 male and 3 female dogs was maintained on a diet of Allied Mills — Tail Wagger Dog Food-Krums to which was added 5.0 weight per cent of Wesson Oil. In Experimental Groups I, II and III there were four male and three female dogs, three male and three female dogs, and three male and two female dogs respectively. They were maintained on the same diet as the Control Group except that di-(3,5-di-tert-butyl-4-hydroxyphenyl)methane was added to the extent of 0.3, 1.0 and 3.0 weight per cent, based on the weight of the dog food, respectively. The compound was added by dissolving it in the Wesson Oil up to the limit of solubility and thereafter thoroughly mixing any additional amount of compound with the dog food. The dogs had an average weight of 8 kilograms and ate an average of 200 grams of dog food per day. After 30 days, samples of plasma and serum were taken and the serum analyzed for total lipid, total cholesterol, free cholesterol and cholesterol-ester values. The results are summarized in Table I.

TABLE I

Group	No. Dogs	Serum Lipid Levels ⁽¹⁾ - 30 Days				
		Per Cent ⁽²⁾	Total Lipids	Total Cholesterol	Free Cholesterol	Ester Cholesterol
Control	6	—	694	120	31	89
Experimental I	7	0.3	465	56	12	44
Experimental II	6	1.0	495	36	8	32
Experimental III	5	3.0	377	43	8	35

⁽²⁾Per cent of di-(3,5-di-tert-butyl-4-hydroxyphenyl)methane based on the weight of the diet.

longer a gray solid separated. This mixture was heated with stirring for 1 hour at 60°. The cooled mixture was then treated with 31.2 g (0.2 mole) of ethyl iodide. This addition took six minutes and an ice bath was needed to keep the temperature below 55°. After the mixture began to cool, it was heated at 60° for one hour. The deep red color which formed on addition of the ethyl iodide disappeared after about 40 minutes of heating. The yellow mixture which remained formed a yellow solid on cooling. The mixture was treated with water and extracted with chloroform several times. The chloroform extracts were washed with water, dried with

65 After 90 days of being maintained on the above diets, dogs in the Control Group and Experimental Group III were sacrificed and their plasma and serum were analyzed for cholesterol, phospholipid and triglyceride values. The results are summarized in Table II.

⁽¹⁾Means values, expressed as Mg. of lipid/100 ml. of serum.

Residual serum from the dogs of the Control Group and Experimental Group III were separately pooled and the amount of α - and β -lipoprotein in the serum for each group was determined by ultracentrifugation. The results are summarized in Table III.

TABLE III

Group	Serum Lipoprotein Values ⁽¹⁾ - 90 Days	
	Total α -Lipoprotein	Total β -Lipoprotein
Control	355	139
Experimental III	178	41

⁽¹⁾Values expressed as mg. of lipoprotein/100 ml. of serum.

These results demonstrate outstanding reductions in all lipid and lipoprotein values by use of a compound of this invention. Particularly notable is the great reduction in the β -lipoprotein values. High β -lipoprotein values are generally associated with atherosclerosis in man.

In addition to the above tests the nonsaponifiable fraction of the serum of one of the dogs in Experimental Group III was analyzed for abnormal sterols such as desmosterol. No evidence of the presence of any ab-

The compounds are administered internally and may be parenterally or orally administered, the latter being preferable. The compounds of this invention are generally solid at room temperature and for oral administration pharmaceutical preparations of this invention may be made following conventional techniques of the pharmaceutical chemist. These techniques involve granulating and compressing when necessary or variously mixing and dissolving or suspending the ingredients as appropriate to the desired end product. Numerous pharmaceutical forms to carry the compounds can be used. For example, the pure compound can be used or it can be mixed with a solid carrier. Generally, inorganic pharmaceutical carriers are preferable and particularly solid inorganic carriers.

In other tests which show effectiveness of the compositions and methods of this invention, test materials were administered daily to pure bred male beagle dogs. In some instances the test compound was given by capsule 125 mg/kg of body weight. In other instances the compound was admixed with the diet. The concentration of the test chemical in the diet was based on the dog's previous food consumption and provided approximately 125 mg/kg of body weight.

The test diets were prepared by dissolving or suspending the test compound in Mazola Corn Oil followed by heating to 93°-97°C. for up to 30 minutes and mixing with the feed (Wayne Dog Food, Krum's, meal). All diets contained corn oil at the concentration of 5 percent by weight.

The dogs were fed ad libitum for one hour each day from pre-weighed food hoppers. Water was available ad libitum.

Results are summarized in the following table.

CHOLESTEROL VALUES IN MG/100 ML SERUM

Compound	Dog	Baseline Values		Baseline Avg.	Compound Administration In Capsules Weeks	Compound Administered In oil mixed with Diet Weeks		
		2	4			1	2	3
A	1	144	153	182	171	162	128	151
A	2	141	127	121	122	128	116	151

*data not used in calculating averages

Compound A - 2,2'-methylenebis(6-tert-butyl-4-chlorophenol)
 Compound B - 2,2'-methylenebis(6-tert-butyl-p-cresol)
 Compound C - 4,4'-methylenebis[2,6-bis(α -methylbenzyl)phenol]
 Compound D - 2-tert-butyl-4,4'-methylene diphenol
 Compound E - 4,4'-isopropylidenebis(2,6-di-tert-butylphenol)
 Compound F - 4,4'-methylenebis(2,6-di-sec-butylphenol)

normal sterol was found, showing that the effect of the compound on the biosynthesis of cholesterol is most likely at an earlier stage than after the cyclization of squalene. Such effects are highly desirable, as the formation of abnormal sterols may produce untoward side effects.

Efficacious results are also obtained with other compounds of this invention and with other mammals such as cattle, sheep, rabbits, and others, and this invention is particularly desirable for treating humans.

For Compound F, the test diet was prepared by dissolving 80 grams of the compound in 920 grams of corn oil and mixing with 19 kg. of Wayne Dog Food, Krum's.

No apparent reason was noted for the inconsistency of hypcholesterolemic response of dogs 5 and 6 for Compound C. However, for Compound D, results indicated that the dog with a greater hypcholesterolemia received an average dose of 106/mg/kg/day while dog 7 received an average dose of 81 mg/kg/day. Also, the dogs on Compound A rejected the test diet.

Dogs maintained on diets containing up to 3.0 weight per cent of di-(3,5-di-tert-butyl-4-hydroxyphenyl)methane for 90 days have shown no adverse effect on growth or behavior. When sacrificed at the end of 90 days there were no gross or microscopic pathology attributable to the di-(3,5-di-tert-butyl-4-hydroxyphenyl)methane. The acute LD₅₀ in rats is greater than 15 gms/kg. Rats fed on a diet containing substantial amounts of di-(3,5-di-tert-butyl-4-hydroxyphenyl)methane for 90 days suffered no grossly harmful effects. There were no changes in prothrombin time, hematocrit, hemoglobin or white blood counts. At 1.25 weight per cent of the diet there were no gross or histopathological changes.

For the compound 4,4'-ethylenbis(2,6-di-tert-butyl-phenol), the test diet, which provided a daily dose of approximately 125 ± 30 mg/kg, was given to dog (i) for a 7 week period except for 3 days after the end of the fourth week. The test diet was fed to dog (ii) for 4 weeks, control diet during the fifth week, and test diet on Monday, Wednesday, and Friday during the sixth and seventh weeks with control diet on alternate days. Results were as follows:

Cholesterol Values in mg/100 ml Serum

Average Baseline	Dog No.	1	2	3	4*	5	6	7
163	i	117	175	133	158	127	140	122
161	ii	128	164	94	76	111	152	104

*4 weeks plus 2 days

After seven weeks, alkaline phosphatase levels on both dogs were run and found to be elevated. Elevation of serum alkaline phosphatase was also noted on other dogs who had exhibited a hypocholesterolemic effect upon being treated with methylenebis-(2,6-di-tert-butylphenol). Based on such evidence, it appears that in dogs treated with this compound, cholesterol lowering may be associated with increase in alkaline phosphatase; however, this observation has not been made in man. Thus, except for possibly one instance, there have not been any cases of increases in alkaline phosphatase during the term of administration of the drug in man, even in the presence of significant lowering of cholesterol and other lipids.

cholesterol and other lipids. There have been clinical studies using methylenebis-(2,6-di-*tert*-butylphenol) in man. These studies show that reductions in serum lipids from the drug can be obtained in man using 0.1, 0.25, 0.5 and 1.0 grams of the compound per day. For example, in one group of 13 geriatric patients, the average initial total serum cholesterol was 244 mg per cent in a control period extending over six weeks. The drug caused a fall to a mean level of 181 mg per cent when the drug was given over a four week period.

In another study with healthy volunteers receiving 0.1, 0.5 and 1.0 grams of drug per day over the four week period of drug administration, the average reduction in serum cholesterol expressed in milligram per 100 ml of serum was 12, 26, and 35 respectively.

All the side effects noted in the clinical studies were in the group of 13 geriatric patients. Three patients complained of epigastric burning, anorexia, nausea and occasional vomiting. The symptoms were obviated by administration of the drug with meals. No alteration in the hypcholesterolemic potency was observed by giving the drug with meals. The appearance of periorbital edema was reported in two of the 13 patients. In one patient there was a probable potentiation of anticoag-

ulant therapy. Two cases of pneumonia; one resulting in death in a severely ill elderly patient, occurred while patients were on drugs but are not considered to be related to drug administration.

5 In the terminal case, the patient was a 69 year old male with hypertension, generalized arteriosclerosis obliterans and right hemiplegia. Terminally, his SGOT was 135, the alkaline phosphatase 20 Bodansky units, prothrombin time 17/14 and an inverted A/G ratio. Ke-
10 tosteroid excretion was increased from 7.7 mg/gm creatinine on 1/26/65 to 18.6 mg/gm creatinine (terminal). Pneumonia is not an uncommon complication in elderly patients and is often the cause of death in hemiplegic individuals.

15 The side effects and clinical course of patients in the group of geriatric patients are noted above. A careful toxicologic evaluation of renal, liver, bone marrow, and adrenal function (ketosteroid and 17-oxycorticoid excretion) in these patients has failed to demonstrate ab-
20 normalities definitely related to the drug.

Serum lipid levels can be reduced by internally administering to a mammal a composition having a serum lipid lowering amount of the galvinoxyl radical.

40 where $t\text{-C}_3\text{H}_9$ is a tert-butyl group. The galvanoxyl radical may be referred to as 2,6-di-tert-butyl- α -(3,5-di-tert-butyl-4-oxo-2,5-cyclohexadien-1-ylidene)-p-toloxoxy.

45 Thus, in a test similar to the above with male beagle dogs and 0.4 per cent by weight of the compound mixed with the diet, the following results were obtained.

Cholesterol Values in mg/100 ml Serum

Dog	Baseline Average	Weeks on Diet		
		1	2	4
A	154	122	127	127
B	232	208	243	197

60 Compositions containing the galvinoxyl radicals are illustrated by those made by substituting the radical for the active ingredient in Examples 1-11 which follow.

The compounds are administered internally and may be parenterally or orally administered, the latter being preferable. The compounds of this invention are generally solid at room temperature and for oral administration pharmaceutical preparations of this invention may be made following conventional techniques of the pharmaceutical chemist. These techniques involve granulating and compressing when necessary or vari-

ously mixing and dissolving or suspending the ingredients as appropriate to the desired end product. Numerous pharmaceutical forms to carry the compounds can be used. For example, the pure compound can be used or it can be mixed with a solid carrier. Generally, inorganic pharmaceutical carriers are preferable and particularly solid inorganic carriers. One reason for this is the large number of pharmaceutically acceptable inorganic materials which are known to be pharmaceutically safe and acceptable, as well as very convenient in preparing formulations. The compositions may take the form of tablets, linguets, powders, capsules, slurries, troches, or lozenges, prepared by standard pharmaceutical techniques. Tablet compositions may be coated or uncoated and they may be effervescent or non-effervescent. Conventional excipients for tablet formations may be used. For example, inert diluents, such as magnesium carbonate or lactose, disintegrating agents such as maize starch or alginic acid, and lubricating agents such as magnesium stearate may be used. A preferable tablet composition is one which comprises from about 10 to about 500 milligrams of di-(hydroxyphenyl)methane, particularly di-(3,5-di-tert-butyl-4-hydroxyphenyl)methane.

If a liquid carrier is used, the preparation may be in the form of a soft gelatin capsule, a syrup, a liquid solution or suspension. Most of the compounds of this invention are only slightly soluble in water, if at all, but are generally soluble in alcohols particularly glycols, to some extent. In general, those di-(hydroxyphenyl)methanes having greater hydrocarbon substitution are less soluble in water. Di-(3,5-di-tert-butyl-4-hydroxyphenyl)methane, for example, is insoluble in water, but is soluble in ethyl alcohol to the extent of about six weight per cent. The hydrocarbon solubility of most of the compounds of this invention is high enough to allow the use of various pharmaceutically acceptable oils as carriers. For example, vegetable or animal oils such as sunflower oil, safflower oil, maize oil or codliver oil can be used. Glycerine can also be used. With these latter solvents, from 25-30 per cent water may be added. When water alone is the carrier, the preparation can be administered in the form of a slurry.

Emulsion compositions may be formulated using emulsifying agents such as sorbitan tri-oleate, polyoxyethylene sorbitan monooleate, lecithin, gum acacia or gum tragacanth. Aqueous based suspensions may be prepared with the aid of wetting agents such as polyethylene oxide condensation products of alkylphenols, fatty alcohols or fatty acids and with suspending agents, for example, a hydrophilic colloid such as polyvinyl-pyrrolidone. The emulsions and suspensions may contain conventional excipients such as sweetening agents, flowing agents, coloring materials and preservatives.

The compounds of this invention may be administered in the form of a nutritive preparation in which the mixture of active ingredients is mixed with proteins, such as casein and carbohydrates. In addition to the active ingredients, dietary supplements such as vitamins, salts of glycerophosphoric acid, choline, inositol and amino acids such as methionine may be added.

The percentage of di-(hydroxyphenyl)methane in the pharmaceutical carrier may be varied. It is necessary that the di-(hydroxyphenyl)methane constitute a proportion such that a suitable dosage will be obtained. It is therefore preferred to use pharmaceutical compositions containing at least 10 weight per cent of the

di-(hydroxyphenyl)methane. Activity increases with concentration of the agent in the carrier, but those compositions containing a significant amount of carrier, e.g. at least 1 per cent and preferably at least 5 per cent, are preferred as they allow for the easier administration of the di-(hydroxyphenyl)methane.

For parenteral use, the compounds of this invention can be formulated with sterile ingredients, compounds and packaged aseptically. They may be administered 10 intravenously or intramuscularly. Useful solvents for formulation in such use are the polyhydric aliphatic alcohols and mixtures thereof. Especially satisfactory are the pharmaceutically acceptable glycols, such as propylene glycol, and mixtures thereof. Glycerine is another 15 example of a polyol which is particularly useful. Up to 25-30 per cent by volume of water may be incorporated in the vehicle if desired. An 80 per cent aqueous propylene glycol solution is a particularly convenient 20 solvent system. A pH range, about 7.4, and isotonicity compatible with body isotonicity is desirable. Basicity may be controlled by addition of a base as required, and a particularly convenient base is monoethanolamine. It may often be desirable to incorporate a local 25 anaesthetic and such are well known to those skilled in the art. For example, lidocaine (β -diethylamine-2,6-acetoxylidide, available from the Astra Chemical Company) may be employed at a level of up to about 20 mg/c.c., or even more.

Administration of the compounds of this invention by 30 the oral route is preferred. Advantageous daily dosages can be as low as 150 mg. for a human. Higher dosages can be used. Generally, one would choose to use the least amount which affords the desired magnitude of sought-after result. Such practice tends to minimize 35 chances of appearance of undesirable side effects. A preferred range of daily dosage is about 0.25 to 7.5 grams. In terms of body weight, advantageous dosages are from 2.5 to 1,000 mg. per kg. of body weight per day with a preferred range of about 25 to 125 mg. per 40 kg. of body weight per day. The daily dosage is preferably administered from one to four or five times daily in amounts of from about 150 mg. to about 2,000 mg., and these amounts are administered in dosage units 45 containing at least 10 mg. of the di-(hydroxyphenyl)methane. For example, when administering the compound in tablet form several tablets containing from, say 10 to 25 mg. of active compound can be administered, up to 4 or more times daily. Alternatively, larger dosage units containing more of the di(hydroxyphenyl)methane, say 50 to 500 mg. can be administered 50 at less frequent intervals.

For parenteral applications daily dosages of about one-tenth of that used for oral treatment are advantageous. Thus, daily dosages can be as low as 15 mg. for a human, i.e. 0.25 mg. per kg. of body weight. A convenient upper limit is about 6 grams. From about 5 to about 1000 mg. per injection (dosage unit) in concentrations of about 5 to 200 mg/c.c., with from 1 to 3 injections of from 1 c.c. to 10 c.c. daily will give the required amount. Preferred formulations will contain from 50 to about 150 mg./c.c. to be given in one injection of from 1 c.c. to 5 c.c.

The oral or parenteral dose may be individually determined by the physician or veterinarian. Larger or smaller doses can be used and, in some cases, might be preferred in individual cases. Likewise, administration need not be on a daily basis, although this is preferred,

but may be, for example, on alternate days or even weekly and the like. With either oral or parenteral use, a daily regimen is preferred. However, even a single administration has some effect.

The following examples are not limiting but are illustrative of compounds and pharmaceutical preparations useful in this invention.

EXAMPLE 1

Di(3,5-di-tert-butyl-4-hydroxyphenyl)methane is compressed into tablets of 100 mg. each which can be administered orally as antihypercholesterolemic agents.

EXAMPLE 2

300 Mg. of 4,4'-ethylidenebis(2,6-di-tert-butylphenol) are filled into a No. 2 hard gelatin capsule.

EXAMPLE 3

50 Gms. of 4,4'-isopropylidenebis(2,6-di-tert-butylphenol), 10 gms. of calcium sulfate and 25 gms. of sucrose are thoroughly mixed and granulated with hot 10 per cent gelatin solution. The wetted mass is passed through a No. 16 U.S. standard mesh screen directly onto drying trays. The granules are dried at 120°F. and passed through a No. 20 U.S. standard mesh screen. These granules are then mixed with 15 gms. starch, 5 gms. talc and 3 gms. stearic acid, passed through a No. 60 U.S. standard mesh screen and then compressed into tablets containing 150 mg. of active ingredient.

EXAMPLE 4

75 Mg. of 2-tert-butyl-4,4'-methylenediphenol are mixed with 225 mg. of peanut oil to a thick slurry and filled into a soft gelatin capsule.

EXAMPLE 5

Linguets are obtained by combining the following components:

4,4'-methylenedi-2,6-xylenol, mg.	25
Lactose, mg.	50
Confectioner's sugar, mg.	60
Stearin, mg.	2
Talc, mg.	13

EXAMPLE 6

To a mixture of 140 gms. of 2,2'-methylenebis(6-tert-butyl-4-chlorophenol) and 33.7 gms. of corn oil are added 3 gms. of gum acacia and 1.5 gms. of gum tragacanth. To the thoroughly triturated mixture is added slowly with stirring a solution of 0.1 gms. of a cetyl alcohol polyoxyethylene condensate, 40 gms. of can sugar, 0.03 gms. of propyl-p-hydroxybenzoate, 0.3 gms. of methyl-p-hydroxybenzoate, 0.002 g. of edible dyestuff and 110 gms. of water. After the incorporation of a suitable flavoring agent, such as imitation wild cherry, the mixture is homogenized by passage through a conventional homogenizer and there is thus obtained an emulsion suitable for oral administration in accordance with the present invention. The emulsion is bottled in half-pint bottles.

EXAMPLE 7

10 Gms. of 4,4'-methylenebis[2,6-bis(α-

methylbenzyl)-phenol] are dissolved in a mixture of 83 grms. of water, 250 gms. glycerol and 125 gms. of ethyl alcohol. To the resultant solution is added to a solution of 300 gms. of sucrose and 150 gms. of water. By the incorporation of a suitable flavoring agent and coloring material there is obtained a syrup suitable for oral administration in accordance with the present invention.

EXAMPLE 8

10 25 Gms. of sodium glycerophosphate, 25 gms. of calcium glycerophosphate and 50 mgs. of 4,4'-methylenebis(2,6-di-sec-butylphenol) are intimately mixed. The mixture is added gradually to 900 gms. of soluble casein in a conventional mixer and mixed until 15 homogenous. There is thus obtained a dietary supplement suitable for oral administration in accordance with this invention.

EXAMPLE 9

20 25 An intimate mixture is prepared with conventional mixing equipment of 3 gms. of pyridoxine hydrochloride, 100 gms. of nicotinic acid, 100 gms. of nicotinamide, 5 gms. of methionine, 15 gms. of choline bitartrate, 150 mgs. of ascorbic acid, 5 gms. of calcium pantothenate, 10 gms. of riboflavin and 1,000 gms. of bis(3,5-di-tert-butyl-4-ethoxyphenyl)methane. The mixture is filled into capsules which are then suitable for oral administration in accordance with this invention.

EXAMPLE 10

30 35 382 Gms. of propylene glycol are agitated for one hour while saturating with nitrogen gas. 12.4 Gms. of 4,4'-methylenebis (2,6-di-tert-butylphenol) are then added and the mixture is stirred for 30 minutes more. Then 95 c.c. of nitrogen saturated water is slowly added. After 5 minutes of further stirring 7.85 c.c. of monoethanolamine is added. Throughout the addition of ingredients the temperature is maintained below 30°C. by cooling as required. Solution is completed by stirring under nitrogen. The resulting 500 c.c. of clear, light-colored solution contains approximately 50 mg./c.c. of 4,4'-methylenebis-(2,6-di-tert-butylphenol) and is slightly alkaline. It is subdivided and samples are 40 45 filled under nitrogen into 10 c.c. multi-dose vials sealed with butyl rubber stoppers. 3 C.C. doses can be withdrawn in the standard manner, by piercing the stopper with a hypodermic needle, injecting air and withdrawing the solution into the syringe. In this manner parenteral doses containing 150 mg. of 4,4'-methylenebis(2,6-di-tert-butylphenol) are provided.

EXAMPLE 11

55 4,4'-methylenebis(2,6-di-tert-butylphenol) gms.	66.6
Monoethanolamine, c.c.	22.1
Lidocaine, gm.	10
Propylene glycol, gm.	275
Water to make 400 c.c.'s	

60 65 The above solution contains 150 mgs./c.c. of 4,4'-methylenebis-(2,6-di-tert-butylphenol) and can be administered intramuscularly in 1 c.c. doses, once a day, giving a daily dosage of 150 mgs.

In general, solid dosage forms contain from 5 to 60 per cent of active ingredient while liquid dosage forms usually contain 1 to 20 per cent active ingredient. Greater or lesser amounts can be employed.

Thus, preferred embodiments of this invention are: A method of treating a mammal whose serum lipid level is to be reduced which comprises internally administering to said mammal a serum lipid-lowering amount of a compound having the formula

wherein

R^a and R^b are tert-butyl,
R and R^c are alkyl of 1 to 4 carbons, and R^d and R^e are independently selected from hydrogen or methyl.

This method may be used in treating a mammal with elevated or abnormally high lipid levels, as well as those having normal amounts of lipid.

Such method can comprise internally administering to a mammal the following compounds of the above formula (II).

di-(3,5-di-tert-butyl-4-hydroxyphenyl)methane
4,4'-isopropylidenebis(2,6-di-tert-butylphenol)
4,4'-ethylidenebis(2,6-di-tert-butylphenol)
4,4'-methylenebis(2,6-di-sec-butylphenol)

Also, this invention comprises the preferred methods of treating a mammal whose serum lipid level is to be reduced which comprises internally administering to said mammal a serum lipid-lowering amount of

[2,6-bis-(α -methylbenzyl)phenol],
2-tert-butyl-4,4'-methylenediphenol,
2,2'-methylenebis(6-tert-butyl-4-chlorophenol),
2,2'-methylenebis(6-tert-butyl-p-cresol), or
bis(3,5-di-tert-butyl-4-ethoxyphenyl)methane.

In another preferred embodiment, I provide therapeutic compositions effective in lowering serum lipid levels in mammals which comprise from 5 to 500 milligrams of a compound of Formula IV and a significant amount of a pharmaceutical carrier. Thus, for example, I provide such compositions where said compound is di-(3,5-di-tert-butyl-4-hydroxyphenyl)methane. Also, I provide such compositions having at least 10 weight per cent of a compound of Formula IV and at least 5 per cent by weight of a pharmaceutically acceptable carrier. These compositions may be in capsule form or tablet form. For example, such capsules may contain the compound di-(3,5-di-tert-butyl-4-hydroxyphenyl)methane.

Also, there is provided therapeutic compositions having at least 10 weight per cent of a compound of Formula IV and at least 5 per cent by weight of a pharmaceutically acceptable carrier,

- wherein R^a in said formula is methyl,
- wherein R^b in said formula is methyl,

- wherein R^d in said formula is hydrogen,
- wherein R^e in said formula is hydrogen,
- wherein R and R^c in said formula are methyl,
- wherein R and R^c in said formula are butyl,
- wherein the compound is 4,4'-isopropylidenebis(2,6-di-tert-butylphenol)
- wherein the compound is 4,4'-ethylidenebis(2,6-di-tert-butylphenol), and
- wherein the compound is 4,4'-methylenebis(2,6-di-sec-butylphenol).

Also, there is provided therapeutic compositions having at least 5 per cent by weight of a pharmaceutically acceptable carrier and at least 10 weight per cent of a compound such as

- di-(3,5-di-tert-butyl-4-hydroxyphenyl)methane
- 4,4'-methylenebis[2,6-bis(α -methylbenzyl)phenol]
- 2,2'-methylenebis(6-tert-butyl-4-chlorophenol)
- bis(3,5-di-tert-butyl-4-ethoxyphenyl)methane
- 2-tert-butyl-4,4'-methylenediphenol, or
- 2,2'-methylene(6-tert-butyl-p-cresol).

The therapeutic compositions discussed above are preferably in unit dosage form. Typical dosage forms are exemplified by Examples 1-11 above.

Above, when clinical testing was discussed, a case was mentioned of a possible increase in alkaline phosphatase in man. This case was a healthy volunteer who showed an increase after receiving for 4 weeks 1.0 gram daily of methylenebis(2,6-di-tert-butylphenol). However, repeat determinations of alkaline phosphatase were normal, and the subject remained asymptomatic.

I claim:

1. A method of treating a mammal whose serum lipid level is to be reduced which comprises internally administering to said mammal, in unit dosage form a serum lipid-lowering amount of a compound having the formula

40

50 wherein

- R^a and R^b are tert-butyl,
- R and R^c are alkyl of 1 to 4 carbons, and
- R^d and R^e are independently selected from hydrogen or methyl.
- The method of claim 1 wherein said compound is di-(3,5-di-tert-butyl-4-hydroxyphenyl)methane.
- A method of treating a dog whose plasma lipid level is to be reduced, which comprises internally administering from about 0.25 mg. to about 1.0 gram of di-(3,5-di-tert-butyl-4-hydroxyphenyl)methane per kilogram of body weight per day.
- The method of claim 1 wherein R^a is methyl.
- The method of claim 4 wherein R^e is methyl.
- The method of claim 1 wherein R^d is hydrogen.
- The method of claim 6 wherein R^e is hydrogen.
- The method of claim 1 wherein R and R^c are methyl.

9. The method of claim 1 wherein R and R^c are butyl.
 10. The method of claim 1 wherein said compound is 4,4'-isopropylidenebis(2,6-di-tert-butylphenol).

11. A method of treating a mammal, in unit dosage form whose serum lipid level is to be reduced which comprises internally administering to said mammal a serum lipid-lowering amount of 4,4'-methylene-bis[2,6-bis-(α -methylbenzyl)phenol].

12. A method of treating a mammal, in unit dosage form whose serum lipid level is to be reduced which comprises internally administering to said mammal a serum lipid-lowering amount of 2,2'-methylene-bis(6-tert-butyl-4-chlorophenol).

13. A method of treating a mammal, in unit dosage form whose serum lipid level is to be reduced which comprises internally administering to said mammal a lipid-lowering amount of bis(3,5-di-tert-butyl-4-ethoxyphenyl)methane.

14. A method of treating a mammal, in unit dosage form whose serum lipid level is to be reduced which comprises internally administering to said mammal a serum lipid-lowering amount of 2-tert-butyl-4,4'-methylenediphenol.

15. A method of treating a mammal, in unit dosage form whose serum lipid level is to be reduced which comprises internally administering to said mammal a serum lipid-lowering amount of 2,2'-methylene-bis(6-tert-butyl-p-cresol).

16. A therapeutic composition in unit dosage form having at least 10 per cent by weight of 4,4'-methylenebis[2,6-bis(α -methylbenzyl)phenol] with at least 5 per cent by weight of a pharmaceutically acceptable carrier.

17. A therapeutic composition in unit dosage form having at least 10 per cent by weight of 2-tert-butyl-4,4'-methylenediphenol with at least 5 per cent by weight of a pharmaceutically acceptable carrier.

18. A method of treating a mammal whose serum lipid level is to be reduced which comprises internally administering to said mammal, in unit dosage form, a serum lipid-lowering amount of 4,4'-ethylidenebis(2,6-di-tert-butylphenol).

19. A method of treating a mammal whose serum lipid level is to be reduced which comprises internally administering to said mammal, in unit dosage form, a serum lipid-lowering amount of 4,4'-methylenebis(2,6-di-sec-butylphenol).

20. The method of claim 1 wherein said compound is 4,4'-methylene bis(2-ethyl-6-tert-butylphenol).

21. The method of claim 1 wherein said compound is 4,4'-methylene bis(2-isopropyl-6-tert-butylphenol).

22. The method of claim 6 in which R is the same as R^c.

23. The method of claim 7 in which R is the same as R^c.
